UNITED STATES PATENT OFFICE

DAVID GEORGE, OF SWANSEA, WALES

METHOD AND APPARATUS FOR CLOSING METALLIC PACKAGES

Application filed February 25, 1928, Serial No. 257,027, and in Great Britain March 16, 1927.

This invention relates to the packing of relatively heavy articles, such as tinplates, terneplates, blackplates and the like, and has for its object to provide improved forms of packing and apparatus for closing such packing, whereby the packing of articles of the kind described will be considerably cheaper than hitherto, while the package itself will be more reliable than those at present on the market.

10 The invention consists in a method of forming or closing a package or container comprising providing a tubular member of sheet metal, inserting into the open end of such tubular member an end closing plate having outwardly extending flanges so that such flanges lie parallel with the marginal portions of the walls of such member and rolling together said flanges and marginal portions.

20 According to the present invention the package or container comprises a tubular member formed of tinplate, terneplate or other suitable sheet metal, and end closing plates adapted to close such member, the edges of the tubular member and of the end plates being rolled together whereby the package is closed.

25 The package may comprise the sole covering or may form the inner or outer casing in forms of packing such as described in my prior patents, or other forms of packing comprising inner and outer cases.

30 The improved package may be hermetically sealed by soldering the rolled edges and the joints.

35 The invention also consists in means for rolling the edges of the ends of the container comprising a member or closing tool provided with a roll-forming groove (or grooves) and adapted simultaneously to roll all the edges at one end of the package.

40 The parts of the tubular member and end plates forming the rolls may be suitably cut to form mitred rolls at the corners of the package.

45 In the accompanying drawings:—

50 Figure 1 shows in perspective the upper end of a tubular enclosing member according to the invention.

Figure 2 shows in perspective an end closing plate therefor.

Figures 3, 4 and 5 are respectively side elevation, front elevation and plan of a machine for closing the cases according to the invention.

Figures 6, 7 and 8 are respectively sectional, side and end elevations and plan of a closing tool.

Figures 9 and 10 are sectional elevations showing the method of closing a case according to the invention.

55 In carrying the invention into effect according to one form, as in the manufacture of an inner hermetically sealed casing for containing tinplates, terneplates, blackplates or other metallic sheets, a tube 11 of rectangular cross section is provided and is formed from tinplate, terneplate, or other suitable sheet metal.

60 The length of the tube is equal to the length of the plates to be packed therein, plus an allowance (1) at each end for the portion of, say, $\frac{1}{2}$ inch to $\frac{3}{4}$ inch, adapted to be turned in to form the bead or roll by which the ends of the case are secured, (2) for the thickness of any buffer or buffers and/or packing strip or packing strips which may be intended to be inserted inside the case, and (3) for the thickness of the end closing plate.

65 The longer dimension of the cross section of the tube is equal to the width of the plates intended to be packed in the case, plus the thickness of any buffers or packing strips which may be intended to be inserted between the edges of the plates, and the sides of the case. The shorter dimension of the cross section of the tube is equal to the aggregate thickness of the bundle of plates intended to be packed in the case (plus similar allowances if any buffer or buffers and/or packing strip or strips and/or sheet or sheets are used on the top and/or bottom of the bundle of plates intended to be packed in the case.)

70 The seam indicated diagrammatically at 12 formed in making the tube by joining the edges of the sheet out of which the tube is formed may be an ordinary double seam, formed by any known method and may be 130

located along one of the wider sides of the tube and parallel to the axis of the tube as shown or along one of the narrower sides of the tube.

Before the tube is formed, the sheet out of which it is formed has four more or less V-shaped nicks 13 cut in it on each side in such positions that the bottoms of the V's come exactly at the corners of the tube when formed, as shown in Figure 1. The depth of the nick is about $\frac{1}{2}$ an inch but may vary according to circumstances.

The position of the bottom of the nick may vary with regard to the finished roll and may be at the level of the centre of the roll or at the level of the top of the roll.

The edges of the sheet which will form the ends of the tube are preferably provided with an appreciable burr or bevel or are tipped on the side of the plate which will form the inside of the tube, in order that when the tube is formed the outside surfaces of the extreme ends of the case will be bent inwards, as will be seen at 14 Figure 9. This can be effected by means of a tipping machine or by cutting the plates with a shears having a suitable small clearance between blades, or by cutting the plates in a shears having its shear-blades moving in a plane which is at an acute angle with the plane of the body of the plate. The effect of the burr, or of shearing at such an angle, is to form a short bevel on the edge of the tube.

For the purpose of closing the first end of the tube (which end may, for convenience, be referred to as the bottom end) an end closing plate 15 (Figure 2) is provided, which is stamped out of a sheet of tinplate, terneplate or other suitable sheet metal. The length of the strip forming the end plate is equal to the greater dimension in cross section of the tube, and the width of the strip is equal to the lesser dimension in cross section of the tube, plus a margin of, say, $\frac{3}{8}$ ths to $\frac{5}{8}$ ths of an inch all round.

More or less V-shaped nicks 16 are cut out of the corners of the strip forming the end plates and the sides 17 and ends 18 are turned up at an angle of about 115° to the plane of the strip, as will be seen in Figure 9 with respect to the sides 17. The junction of the sides and ends with the main portion may be a slight curve. The edges of these upturned parts are tipped or bent inwards as shown at 19 Figure 9 in a similar manner as the edges of the tube.

The making of the nicks in the corners of end plates, the bending up of the margins and the tipping of the edges may be effected by a single operation in a suitable press.

The rectangular tube is placed upon a former 20, see Figures 3, 4 and 5 over which the tube fits. For a couple of inches down from the top of the former the former is a fairly close fit for the inside of the tube. The

position of the tube, by regulating the height of the former, or by placing a ridge or stops (adjustable or otherwise) near the foot of the former, is such that the top of the tube is about $\frac{1}{2}$ to $\frac{3}{4}$ of an inch above the level of the top of the former.

The long sides of the tube are adapted to be gripped by "grippers", or jaws 21 capable of being brought into close contact with, and exerting pressure upon, the tube, and pressing it against the former, the object of the grippers being to prevent the tube being forced down or buckled by the vertical pressure exerted upon it in the course of subsequent operations.

The grip upon the tube may be ensured by having slight ridges or slight circular or oval bosses or longitudinal projections on the jaws of the gripper and corresponding grooves or circular or oval depressions on the former so placed that the ridges or bosses fit into corresponding grooves or depressions when the jaws of the gripper are brought into contact with the former, care being taken that the recesses and projections are not deep enough as to cause difficulty in removing the tube from the former.

The top ends of the jaws of the gripper are bevelled off at 22 on the outside to co-operate with bevelled surfaces on a closing tool (hereinafter described) whereby the grippers are forced towards each other to grip the tube. The outer surfaces 23 of the grippers adjacent the bevelled part are adapted to lie substantially parallel when in the gripping position, in which position the surfaces contact with suitable surfaces on the closing tool whereby the grip is maintained for a suitable period.

The gripper jaws are pivoted at 24 upon a suitable base member 25 carrying the former which base member in turn is pivoted upon a shaft 26 or trunnions whereby the apparatus may be tilted to a suitable position for insertion or removal of a tube, such pivoting of the apparatus removing it temporarily from the path of the closing tool. The base member is shaped at 27 to permit the pivotal movement. Springs 28 are provided for normally holding the grippers 21 away from the former a slight distance, for example, about $\frac{1}{8}$ th of an inch.

Instead of the springs 28 the grippers or parts therein may extend below the pivots and be coupled by a common tension spring. The opening and closing of the grippers may be effected by utilizing the pivotal movement of the base member 25 carrying the grippers, whereby the latter are opened or closed by means of eccentrics, cams, levers or the like.

Suitable adjustable stops may be provided to locate the gripper jaws and the base member in the desired positions.

One of the grippers 21 is grooved to ac-

commodate the longitudinal double seam on the tube. If desired, both grippers may be grooved so as to facilitate the insertion of the tube in the former.

5 When the tube has been put into position on the former an end plate is put into the end of the tube so as to rest on the top of the former, see Figure 9, the edges of the end piece being turned upwards and being about 10 $\frac{1}{16}$ th to $\frac{1}{8}$ th of an inch below the upper edge of the tube and the nicks in the end piece corresponding with the nicks in the corners of the tube.

It will be understood that the nicks in the 15 tube and end plate will substantially coincide.

The closing tool, mounted in the bracket 40, is then brought down upon the top of the case by a fly-press or by cams or cranks or by any other suitable means.

20 The closing tool, see Figures 6, 7 and 8, is provided with roll-forming grooves 29 which may be of semicircular or other suitable shape in cross section, and which operate to cause the upstanding ends of the tube and the up- 25 standing edges of the end piece, to bend over and form complete or nearly complete rolls along the sides and ends of the tube as shown in Figure 10.

The tipping of the tube and end plate 30 facilitates the bending over and rolling of the upstanding ends.

The closing or roll-forming tool is provided with downwardly extending side pieces 30 along the longer sides thereof, the lowest 35 part of which, for about an inch, is tapered at 31 to co-operate with the bevelled ends 22 of the grippers. The next parts 32 of the walls are parallel and are adapted to engage the outer surfaces 23 of the grippers to maintain the grip on the tube. Finally, the walls 40 again taper inwardly and terminate in the roll-forming grooves. End pieces 33 are provided to complete the roll-forming grooves, but it is not necessary to extend these down- 45 wardly as it is not found necessary to grip the short sides of the tube.

As the edges curl round into a roll, the edges of the nicked corners of the tube and of the end plates respectively come together, one 50 edge of each nick abutting against the other edge of the same nick, so as to form neatly mitred corners. The end plate, other than the rolls, lies flat, with its plane below the rolls.

55 In some cases where the size of the roll is small it may not be necessary to form the nicks so that a geometrically true mitre is formed, and in such cases the sides of the nicks may be straight. Where, however, the 60 roll is of more or less large diameter the sides of the nicks may be correctly curved to form a close mitred joint. The formation and shape of such sides will be obvious and need not be set out herein.

65 In view of the manner of closing the end

of the case, the importance, in the practical working of the invention, of the tipping on those sides of the sheets which form the ends of the tube, and that it should be on one particular side of the sheet, can be appreciated.

To facilitate the rolling and to prevent the lifting of the end piece 15, a rectangular plunger 34 is fitted in a corresponding aperture at the top of the closing tool. The area of the plunger, in plan, is the area inside the 70 rolls when the closing of the end has been accomplished. The slides 35 of the plunger are vertical and work as a sliding fit in the rectangular aperture in the top of the closing tool, and form the inside walls of the roll-forming groove. The plunger is capable of 75 moving vertically, its bottom face being kept always horizontal, and is normally kept at the bottom of its vertical range of movement by springs 36 of suitable strength.

80 When the closing tool begins its descent upon the end of the tube resting upon the former 20, the plunger 34 comes into contact with the end piece 15 of the case. It comes into contact before the closing tool has descended so far that the edges of the ends of the tube enter the final curving portion or 85 groove 29 of the closing tool. The plunger 34 presses, with the strength of its springs, upon the end piece and keeps the end piece 90 in close contact with the upper end of the former underneath the end piece, and prevents the end piece from buckling when the pressure of the closing tool comes upon the 95 edges of the end plate.

100 When the closing tool has descended to the bottom of its travel and is raised again the pressure of the springs 36 in the plunger, acting through the plunger on the end piece, keeps the partially formed case down until 105 the closing tool has withdrawn far enough to ensure the end of the partially formed case being withdrawn from the inner curved portion of the closing tool.

110 It is obvious that the spring plunger may be replaced by a plunger operated positively by cams, cranks, or other mechanical devices, in such a manner that the plunger shall descend and grip the end piece before the roll-forming portion of the closing tool comes 115 into contact with the edges of the tube and end piece, and remain in contact with the end piece until the roll-forming portion of the closing tool has been withdrawn sufficiently to be free of the partially formed case. A 120 knocking-out device may be provided by any known method whereby the partially formed case would be freed from the plunger should the insides of the roll clip the plunger. Normally the partially formed case would be held 125 by the grippers until the closing tool had been withdrawn sufficiently far to free the closing tool and the plunger from the partially formed case.

130 One end of the case being formed, the par-

5 tially formed case is removed from the former. For this purpose the grips when released by the closing tool are moved away from the former by the springs 28 a sufficient distance to free the partially formed case. The former with the base member 25 is then partially rotated on shaft 26 towards the right as seen in Figure 3 sufficiently to permit of the partially formed case being withdrawn clear of the closing tool and without fouling the tool or its guides. Or, the former may be arranged to permit of its being moved downward into a pit so as to come entirely out of the partially formed case (the latter meanwhile resting on stops) so that the partially formed case can be taken out from between the grippers by moving it horizontally. Or, the closing tool could be made to rise to a sufficient height to permit of the partially formed case being lifted off the former. Or, the former could be arranged to slide horizontally from under the closing tool.

20 In order to facilitate the removal of the partially formed case from the former, an ejecting device may be provided extending upwardly through the former, and adapted to be raised by a hand lever, foot pedal or other convenient arrangement so as to lift the case a short distance whereby the case may 25 then be readily removed by hand.

25 This may comprise a part carried on the former and co-operating with a part carried in the base member 25 and operated by any suitable means.

30 The former 20 may be formed as a cored iron casting and is provided at its bottom end with two or more pins or dowels which fit into holes provided in the base member 25 in order to locate it in the correct position with reference to the closing tool.

35 The partially formed case is now filled with tinplates by any convenient means, buffers and/or packing strips and/or sheets, as described in the earlier specifications or otherwise, being used, if desired, to prevent damage to the corners of the case.

40 The former being removed from the closing machine the partially formed and completely filled case is now placed in the position formerly occupied by the former.

45 In the pivoted base member a number of transversely arranged steel rollers is provided which project slightly above the surface of the base and upon which the filled case is adapted to slide whereby its movement into position is facilitated. In order to locate the filled case in position a pair of longitudinally arranged flanges may be provided forming a groove in which the case is run.

50 The position of the case in the groove may be located by stops which may fit into holes in the base.

55 The stops and flanges may be removable so as not to interfere with the former when such is in position, or the lower end of the

former may be shaped to accommodate such flanges and stops.

60 It is obvious that if the grippers are put into action as they were in the first operation they will compress the partially formed case and may bulge the short sides of the partially formed case outwards.

65 This difficulty may be overcome by laying on the top ends of the plates as they stand on end in the partially formed case a strip of wood which just fills the opening of the partially formed case and is about $\frac{1}{2}$ inch to $\frac{3}{4}$ inch thick. This can be of any ordinary dry wood. In practice soft wood is found most suitable. When the grippers come into action 70 they press the sides of the partially formed case up against the strip of wood so that the strip of wood, which is resting upon the ends of the plates in the partially formed case, cannot be forced downwards. The ridges or 75 bosses on the inside of the grippers assist in preventing the partially formed case from being forced down by the pressure of the closing tool. They are arranged to come just under or to make dents in the side of the strip 80 of wood so as, in either case, to assist in preventing the partially formed case from being forced down.

85 The wooden strips also assist in preventing the bulging of the case and deformation of the short sides thereof when the case is gripped.

90 The sides of the partially formed case stand up about $\frac{1}{2}$ an inch above the strip 95 of wood as it lies on the top of the plates.

95 An end plate is then put on top of the strip of wood and the closing tool is depressed and closes the second end of the partially formed case in exactly the same manner as that in which the first end of the partially formed 100 case was closed.

105 The case can now be hermetically sealed by soldering all round the bottom of the rolls on the four sides of both ends of the case and by soldering the joins between the rolls—the 110 mitred joins in the corners.

115 The thickness of the plunger 34 and the depth of the recess therefor may be arranged so that just prior to the downward limit of movement of the closing tool the plunger contacts with the bottom of the recess and thus a positive pressure is imparted to the plunger. This may be accommodated by the soft wood packing strip which will be slightly compressed. The position of the plunger in the 120 recess may be adjusted by inserting packing piece of metal or by the provision of adjusting screws.

125 The inner case, with the contained plates, is then placed inside an outer case, which may be made in exactly the same manner. It will be obvious that the dimensions of an outer case will be suitably larger than those set out above with reference to an inner case. The inner case would usually be made of tin- 130

plate; the outer case would usually be made of blackplate of a stouter gauge than the tin-plate of which the inner case would usually be formed.

5 Preferably the end of the inner case at which the strip of wood is located would be placed first in the outer case so that when the packing is completed there would be a strip of wood at each end of the plates. This 10 would equalize the protection afforded to the plates by the strips of wood acting as buffers. Any other convenient arrangement of strips or buffers of wood may be adopted.

15 The outer case, where both inner and outer cases are used, can be made according to this invention, and the inner case may be made according to the method the subject of the inventor's previous applications or in any other manner producing a case of similar character. 20 Or, vice versa, the inner case may be made according to the present invention and the outer case may be made in any other manner producing a case of similar character.

25 Instead of the former being vertical, it may facilitate the handling of the partially formed cases to have the former and the direction of travel of the closing tool horizontal, or inclined from the vertical at some intermediate angle. If the horizontal position 30 is adopted, the former or case may rest on a table which may take the place of one of the jaws of the grippers and the other jaw may work on pivots or in vertical slides.

35 In some cases the first operation of closing the bottom end of the case may be effected with the tube vertical, the subsequent end closing of the filled case being effected with the case horizontal.

40 To facilitate handling, the filled cases might be conveyed through an end closing machine whereby lifting of the case by the operator is eliminated.

45 The improved roll-closing, involving as it does, two plates, materially stiffens the ends of the package and also acts as a buffer when the ends of the case are subjected to blows, through impact by falls or otherwise.

50 Any design, stamped, printed, lithographed, stencilled, painted or affixed, by paste or otherwise, to the end pieces are protected against being rubbed off owing to the fact that they lie inside or below a plane touching the outside of the rolls or beading. The maker's name and brand can very conveniently be stamped upon the small end pieces and when the case is closed according to this invention the name and brand cannot well be removed without destroying the case.

55 Cases once opened cannot readily be closed again, and makers can be assured that the contents of the boxes cannot be tampered with en route without the traces of the operation being obvious.

60 As described above, grippers are only used on the sides of the partially and completely

formed cases on which the long sides of the closing tool operate. As the short sides of the closing tool operate upon a length which does not usually exceed two inches, it is not thought necessary to arrange for grippers on these short sides, but they obviously could be so arranged if found necessary or desirable.

70 Instead of actuating the grippers by the roll-forming tool, independent means may be provided for adjusting the position of the gripper with regard to the tube so as to grip the latter. Such means may be operated by levers, cams or other appropriate mechanism.

75 As stated above, it will be obvious that the dimensions of the outer case would be slightly larger than those of the inner case and the necessary parts of the machine, such as the closing tool, may be removable for the insertion of a larger tool suitable for the purpose or, if desired, the outer case when formed 80 according to the present invention, may be constructed on an independent machine of suitable size.

85 In practice the former is lifted off the base 85 on which it is positioned by dowels or pins as above described and the jaws of the grippers are made so that they can be unbolted and other jaws substituted. Further the whole base and grippers may be lifted out as a unit and another of the desired dimensions 90 substituted.

95 Having now described my invention, what I claim as new and desire to secure by Letters Patent is:—

100 1. A method of closing an end of a tubular member by a flanged end piece consisting in mounting the tubular member upon a former with the marginal portions projecting above the former, inserting the flanged end piece into said projecting end portions, so that it 105 contacts with the former, gripping the tubular member laterally to prevent relative longitudinal movement between the tubular member and former, and rolling together the flanges of the end piece and the marginal 110 portions of the tubular member while holding the end piece in contact with the former.

115 2. A method of closing the end of a container having the features claimed in claim 1, and having the articles therein, so that the marginal portions of the tubular member project beyond the contents, which consists in inserting a flanged end piece into said projecting end portions so that it contacts with said contents, gripping the tubular member laterally upon the contents to prevent relative longitudinal movement between the tubular member and the articles therein, and rolling together the flanges of the end piece 120 and the marginal portions of the tubular member while holding the end piece in contact with the articles therein.

125 3. Apparatus for closing the end of a tubular member by an insertible flanged end piece comprising a displaceable roll forming die,

a former upon which the tubular member is adapted to be mounted and laterally displaceable gripping members for gripping the tubular member laterally upon said former.

4. Apparatus for closing the end of a tubular member by an insertible flanged end piece comprising a displaceable roll forming die having a pair of walls, a former upon which the tubular member is adapted to be mounted, and laterally displaceable gripping members adapted to be engaged by the walls of the die upon the downward movement thereof to grip the tubular member upon the former.
5. Apparatus for closing the end of a tubular member by an insertible flanged end piece comprising a displaceable roll forming die having a pair of walls, a former upon which the tubular member is adapted to be mounted, pivotally mounted gripping members adapted to be engaged by the walls of the die upon the downward movement thereof to grip the tubular member upon the former and springs for normally holding the gripping members away from the former.
6. Apparatus for closing the end of a tubular member by an insertible flanged end piece comprising a vertically displaceable roll forming die having a pair of walls, a pivotally mounted base plate, a former mounted thereon and upon which the tubular member is adapted to be mounted, laterally displaceable gripping members pivoted to said base plate, said gripping members being adapted to be engaged by the walls of the die upon the downward movement thereof to grip the tubular member upon the former, and springs connected to the gripping members and the base plate to hold the gripping members normally away from the former.
7. Apparatus for closing the end of a tubular member of rectangular shape in cross section by an insertible flanged end piece comprising a vertically displaceable roll forming die having four rolls forming grooves arranged as a rectangle, a pair of parallel walls on said die extending below the roll forming grooves, a pivotally mounted base plate, a former of rectangular cross section mounted on the base plate and upon which the tubular member is adapted to be mounted, laterally displaceable gripping members pivoted to said base plate, said members being adapted to be engaged by the walls of the die upon downward movement thereof, to grip two sides of the tubular member upon the former, and springs connected to the gripping members and the base plate to hold the gripping members normally away from the former.

In testimony whereof I have signed my name to this specification.

DAVID GEORGE.
